UNITED STATES PATENT OFFICE.

CHARLES S. MUIR, OF CHEVY CHASE, MARYLAND.

GAME.

Application filed December 23, 1922. Serial No. 608,720.

To all whom it may concern:

Be it known that I, CHARLES S. MUIR, a citizen of the United States, residing at Chevy Chase, in the county of Montgomery and State of Maryland, have invented certain new and useful Improvements in Games, of which the following is a specification.

This invention relates to an improvement in games.

The object is to provide a game that will not only amuse, but one which will be instructive and educational in the science of astronomy. It consists of a chart of the sun and the various planets, and an indication of their orbits and various constellations, all of which are named, and direct lines extend from the sun to the nearest planet, and to the remaining planets in order, according to their relative distances from the sun, and thence to the various constellations successively according to their relative remoteness. These lines are divided into stops by stars or other indications; and each planet and constellation also represents a stop in the game, the game being played by a spinner, which on stopping at a number indicates the number of spaces the aeroplane (or other object used in playing the game) moves, certain plays being indicated, for instance, a comet or a meteor or the like which requires that the aeroplane or other device used in playing the game must return to a given point if the stop indicated by the spinner would be where a comet or meteor or other obstruction is located.

In the accompanying drawings:

Fig. 1 is a diagrammatic view of the entire game;

Fig. 2 is a view of the spinner showing one of the several signs of the zodiac;

Fig. 3 is a view of an aeroplane used in playing the game.

The chart viewed in Fig. 1 represents the sun at the center of the various orbits of the planets included in the solar system of the sun, such as Mercury, Venus, the earth, Mars, Jupiter, Saturn, Uranus, and Neptune, whose distance from the sun are in the relative order named. Lines 1, preferably straight, are drawn from the sun first to Mercury, and then from Mercury to Venus and so on, in the order named, indicating the path of the object used in playing the game, such, for instance, as an aeroplane 2 or any other device, the aeroplane being

selected as it carries out the idea of aerial navigation from one celestial body to another.

The spaces or moves on these lines are indicated by stars 3, all of which are stops, as are the various planets and constellations in playing the game.

Some such device as a spinner, well known in various games of chance is employed, such as illustrated at 4 in Figs. 1 and 2, and around the edges of which are indicated the signs of the zodiac, one only, namely Scorpio, being illustrated at 5. These various spaces have the numerals 1 to 12 placed therein, and the hand turning at the pivot 7 is adapted to be spun or whirled, and when it stops, for example at 8 as illustrated, it means the player moves eight spaces. If starting the game, this would bring the player to the point marked 8 on the chart, Fig. 1. Another turn the spinner might stop at 3, and that would bring him to the planet Venus. For the next player, the first spin might stop at 11, in which event the first player's aeroplane would have to go back to the planet Mercury, which would mean that when his turn came again he would have to start from there. If the spinner happened to stop at 5, the player would move five points on the line 1, on his journey through the heavens, and would then have another spin of the hand 6, which might stop at 10, where the indication is "Engine trouble. Lose spin," which would mean that he would lose the move.

Suppose a player's aeroplane had reached Jupiter, and the next move indicated was 9; that would take him to the comet C, and would mean that he would have to volplane back to Mars; and so if a player in the region of Neptune won a number which happened to indicate a stop at the meteor M, it would mean he must return to Saturn, and proceed from there on.

Again on reaching Taurus the bull, if the stop happened to come at that point, the player would have to go back to Canis Major, or the greater dog.

Further on, and approaching Polaris or Northern Star, which is the final destination, between that and the Big Dipper there is a stop indicating "Out of water", and necessitating a return to the Big Dipper.

This game might be continued on indefinitely, and it is obvious that it could be made still more complicated by adding other

obstructions, and even making the return back to the sun, without departing from the spirit of the invention. It is the intention in the game itself to have the actual known distances of the planets and the constellations indicated for the educational value, and also a great deal of additional data, as, for instance, the length of orbit and the speed of the earth and the various planets and the time required to revolve around the sun, such as Neptune, for instance, it requiring one hundred sixty-four years for Neptune to complete its orbit around the sun. So far as possible, there would be some indication of the relative sizes of the planets, also of the sun and moon, as I have attempted to indicate in some measure in Fig. 1 of the drawings. Many of the brighter stars might also be shown.

Likewise in the complete illustration, figures may be shown of the various constellations, such as Leo the lion; Gemini, the twins; Taurus, the bull; Auriga, the shepherd; the Great Bear; Big Dipper; and so on, for the interest it would create, and its educational value to either the child or adult, who upon looking at the diagram will know at a glance what the different constellations are. These various things would be indicated on the drawing, but lack of space prevents.

While I have illustrated and described a spinner as a means for indicating the moves, it is obvious that dice might be employed, or a deck of cards for that matter, or any other means that would determine the move by chance.

I claim:

40 1. An astronomical game including a diagram of celestial bodies and orbits around the sun with planets in their respective

orbits with definite relation to their distances from the sun, a movable object adapted to move from one planet to another, and means 45 for indicating the move of said object with respect to the various celestial bodies indicated on the diagram.

2. A game including a diagram of celestial bodies extending continuously from the 50 celestial body nearest the starting-point, as the sun, thence to the next nearest celestial body, and finally to the most remote body, means for indicating the player's 55 move, and a movable object adapted to be moved to the place defined by the indicating device.

3. A game including a diagram of celestial bodies comprising sun, earth and planets, which revolve around the sun, their 60 respective orbits, and spaced-off lines indicating a course of travel from one, starting with the sun, and extending from one celestial body to another in order of their distance from the sun, means for indicating 65 the move upon the line, and a movable device adapted to be moved thereon, as defined by the indicating device.

4. A game including a diagram of celestial bodies extending continuously from the 70 celestial body nearest the starting-point, as the sun, thence to the next nearest celestial body, and finally to the most remote body, means for indicating the player's 75 move, and a movable object adapted to be moved to the place defined by the indicating device, the travel course passed through comets, meteors and the like at intervals, where directions are provided for the return 80 of the traveling device to an indicated point.

In testimony whereof I affix my signature.

CHARLES S. MUIR.
